tion of Illinois

Application February 4, 1938, Serial No. 74,854

Term of patent 14 years

To all whom it may concern:

Be it known that I, Hildegard Wipperman, a citizen of the United States, residing at Chicago, in the county of Cook, State of Illinois, have invented a new, original, and ornamental Design for a Foundation Garment, of which the following is a specification, reference being had to the accompanying drawing, forming part thereof, in which:

Fig. 1 is a front elevation of a foundation garment showing my new design; and

Fig. 2 is a rear view thereof.

The characteristic feature of my design resides

in the combination, in the foundation garment disclosed, of the specific brassière in which the lower portions of the bust pockets are formed by the upwardly arched edges of the front panel of the garment, and in which the upper portions of the bust pockets as well as the downwardly pointed tabs projecting below said upper portions are formed of contrasting material, as shown.

I claim:

The ornamental design for a foundation garment, substantially as shown and described.
